(57) **CLAIM**

The ornamental design for an automatic pipe cleaner, as shown.

DESCRIPTION

The pipe cleaner is battery operated and can clean the inside and outside of a pipe, such as, a copper pipe, at the same time. Likewise, different accessories allow for cleaning different pipe sizes.

FIG. 1 is a top plan view showing my design;

FIG. 2 is a bottom plan view thereof;

FIG. 3 is a perspective view thereof;

FIG. 4 is a front elevational view thereof; and,

FIG. 5 is a rear elevational view thereof.
